UNITED STATES PATENT OFFICE.

EDWARD ERICKSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

HEEL-BEADING MACHINE.

Application filed December 31, 1924. Serial No. 759,039.

This invention relates to burnishing machines and in particular to machines used to ornament the edges of the heels of boots and shoes.

5 Shoes having leather heels and toplifts are commonly ornamented after they have been burnished by providing an indentation or beading along the sides of the heel adjacent to the corners of the heel breast. It is an object of the invention to provide a simple and inexpensive heel-beading machine which may be used without the application of power by movement of the work with respect to the various tools.

10 The position of these beads or indentations with respect to the adjacent edges of the breast of the heel is varied in accordance with the style of work and the taste of the manufacturer. With this in view, in accordance with features of the invention, novel arrangements are provided for relatively adjusting the tools adapted for beading the lateral surfaces of a heel near the edges at the junction of the heel breast and sides, and gage members co-operating therewith so as to vary the distance between the tools and their respective gage members. Novel tool supporting and heating arrangements are also provided, as will be more 25 fully disclosed in the following specification taken in connection with the accompanying drawings.

30 A novel construction and arrangement for beading the periphery of the toplift which are disclosed herein, are claimed in a divisional application Serial No. 182,853 filed April 11, 1927.

In the drawings,—

Fig. 1 is a perspective view of my novel machine;

Fig. 2 is a section through the tool for beading the peripheral edge of the toplift; and

Fig. 3 is a section through the tool for beading the lateral faces of the heel adjacent to the corners of the heel breast.

The machine comprises a tool for treating the edge of the toplift and another tool for treating the lateral faces of the heel, and these tools are mounted in a convenient relation upon a standard. An adjustable gage is provided for each tool, and means are provided for electrically heating the tool used on the lateral faces of the heel. The illus-

trated toplift tool is freely rotatable upon a shaft and arranged so that the operator may place the tool at one heel breast corner and by a single deft movement cause the tool to bead the toplift around its whole outer periphery. The tool used for the beading of the lateral faces of the heel is a double tool provided with an intermediate gage member capable of use with either part of the tool according to whether the tool is being used for one face or the other of the heel. This gage member is adjustable with respect to the tools. The arms supporting the two sets of tools extend substantially at right angles with respect to each other and the burnishing disks are located upon these arms in planes which are parallel. The resulting arrangement enables the operator to present the work first to one and then to the other of the tools substantially without altering his position.

A standard 10 mounted upon a suitable base 12 which is adapted to be screwed to the top of a bench carries at its upper end a tool-supporting head 14 held upon the standard by a set screw 15. The tool supporting head 14 has a lateral boss 16 for the support of a toplift beading tool mechanism and also has flanges 18, only one of which is shown, for the support of a heel-face beading tool and the rheostat for controlling the electric heating of the latter tool.

From an inspection of Fig. 2, it will be seen that there is provided a supporting stud 20 adjustably held in position in the boss 16 by means of a set screw 22. A toplift tool 23, which preferably is mounted for free rotation upon the stud 20, comprises a disk portion 24, the edge of which is used to indent the work by rolling contact therewith, and a sleeve portion 26 surrounding the stud 20 and this toplift tool is positioned upon the stud by engagement with the head of the stud and the end of the boss 16. The outside of the sleeve portion 26 is threaded and a gage member 28 having the form of a disk is adjustably positioned upon said sleeve by threaded engagement therewith and is held in adjusted position by means of a lock nut 30. It will be noted that the outer periphery of the disk-shaped gage member 28 is smooth and rounded so that there is no danger of marking the work in case the operator allows the shoe 31 to slip and come

into contact with the edge of the gage. As will be seen from Fig. 1, the end of the stud 20 and the end of the toplift beading tool 23 are provided with a screw driver slot 32 to allow the user to hold the tool from rotation when it is desired to adjust the gage member on the sleeve portion 26.

A round plate 40 having a laterally extending arm 42 is used to support a heel face beading tool 43. This round plate 40 is supported upon the tool-carrying head 14 of the machine by means of bolts 44 which pass through the flanges 18 and are used also to support a casing 46 of a rheostat. A control lever 48 allows adjustment of the effect of the rheostat upon a heating unit 49 which is received in a suitable socket in the arm 42 of the plate 40. The arrangement of the parts just described is such that the plate 40 and its laterally extending tool-carrying arm 42 may readily be reversed to suit the needs of a left-handed operator.

The tool 43 for beading the lateral faces of the heel 45 comprises twin beading disks 50 and 52 which are held in position at the outer end of the arm 42 by means of a screw stud 54. A tapered gage member 56 has a body portion 58 which is slotted at 60 and is positioned between the disks 50 and 52 and clamped in position by the screw stud 54 the head of which presses directly against a smooth-edged washer 61. By reason of the provision of the elongated slot 60 the gage member 56 may be moved up and down to vary the effective distance between said gage and the lower operating parts of the disks 50 and 52. At the same time the gage member 56 slightly burnishes the faces of the breast corners. It will be seen that this forms a very simple and effective way for determining the distance from the edge of the breast of the heel to the beading line 57. The electrical heating device for this tool is especially desirable for use with a stationary tool, designed to treat the lateral faces of the heel, which must be moved across the grain of the pieces of leather making up the lifts of the heel.

In the use of the machine the operator will commonly stand in front of the projecting arm 42 which carries the tools for beading the lateral faces of the heels. In this position he is enabled to present first one corner and then the other of the heel to the respective disks of this double tool and to move the heel along the tool by raising it against the gage member 56 in the manner suggested in Fig. 1. The operator will then, substantially without changing his position, present the toplift of the heel to the disk portion 24

of the toplift tool and will rest the tread face of the heel against the flat face of the disk-shaped gage member 28. Having positioned the work originally with the tool in engagement with the toplift at one corner of the heel, the operator passes the work downwardly and across and upwardly in such a manner that the tool is brought into engagement with the whole of the outer periphery of the toplift to produce the beading line 59. The position illustrated in Fig. 1 is intermediate between the extreme positions of the work in this part of the beading operation.

Having thus described the invention, what I claim as new and desire to secure by Letters Patent of the United States is:

1. A beading tool comprising indenting members, a tapered gage member interposed between said indenting members having opposed work-engaging surfaces, means for clamping together the indenting members and the gage member, said clamping means allowing adjustment of the gage member with respect to the indenting members to vary the extent of the tapered portion projecting beyond the indenting members whereby the distance between the effective gaging surfaces of said gage member and the respective indenting members may be varied.

2. A heel-beading tool comprising indenting disks, an interposed gage member having a slotted portion and a tapered portion serving as a gage to locate the indentation in the work with respect to the adjacent edge of the work, and means for clamping said gage member and said indenting disks in adjusted position comprising a stud passing through the slot of the gage member.

3. A heel-beading machine comprising a supporting standard, a plate having a lateral extension mounted upon said standard, a tool for treating the lateral faces of a heel adjacent to the heel breast mounted on said extension, and means for clamping said plate to extend laterally in either of two directions with respect to said standard whereby the position of the tool may be determined to suit the needs of the particular operator.

4. A heel-beading machine comprising a supporting standard, a tool-supporting plate having a lateral extension, electric heating means in said extension, a heel-beading tool supported at the end of the extension, a rheostat for controlling the heat supplied to said heating unit, and common means for clamping the rheostat and the plate to the standard.

In testimony whereof I have signed my name to this specification.

EDWARD ERICKSON.
